ANTIQUE CAR BOUNCE RIDE

William J. Burke, Fond du Lac, Wis., assignor to The
J. E. Burke Company, Fond du Lac, Wis.

Filed Aug. 5, 1971, Ser. No. 169,577

Term of patent 14 years

Int. Cl. D21—02

U.S. Cl. D34—5

FIG. 1 is a front and left side perspective view of an antique car bounce ride showing my new design, the right side being a mirror image thereof;

FIG. 2 is a rear elevational view thereof.

The bottom is plain and unornamented.

I claim:

The ornamental design for an antique car bounce ride, as shown and described.
